GRAIN SEPARATOR.

No. 399,148.

Patented Mar. 5, 1889.

UNITED STATES PATENT OFFICE.

JOHN A. KRAKE, OF BUFFALO, NEW YORK, ASSIGNOR OF ONE-HALF TO
JOSEPH BORK, OF SAME PLACE.

GRAIN-SEPARATOR.

SPECIFICATION forming part of Letters Patent No. 399,148, dated March 5, 1889.

Application filed July 20, 1888. Serial No. 280,491. (No model.)

To all whom it may concern:

Be it known that I, JOHN A. KRAKE, of the city of Buffalo, in the county of Erie and State of New York, have invented new and useful 5 Improvements in Grain-Separators, of which the following is a specification.

This invention relates to certain improvements in that class of grain-separators commonly known as "fanning-mills," in which 10 the grain is passed over a series of vibrating sieves and freed from its light impurities by a blast of air produced by a revolving fan.

The object of my invention is to improve the operation of this class of machines by 15 equalizing the force of the blast over the entire width of the machine, and by improving the mechanism whereby the vibrating sieves are set in motion, and also to improve the construction of the machine in various details.

20 The invention consists of the improvements, which will be hereinafter fully set forth, and pointed out in the claims.

In the accompanying drawings, consisting of two sheets, Figure 1 is a side elevation of 25 my improved grain-separator. Fig. 2 is a side elevation of one of the adjustable hangers supporting the vibrating screens, on an enlarged scale. Fig. 3 is a cross-section thereof in line $x-x$, Fig. 2. Fig. 4 is a longitudinal 30 sectional elevation of the machine. Fig. 5 is a horizontal section of the same. Fig. 6 is a fragmentary perspective view of the feed-board and a portion of the casing of the machine. Fig. 7 is a fragmentary sectional elevation of the hub of the fan.

35 Like letters of reference refer to like parts in the several figures.

A represents the stationary frame of the machine; a , the side boards of the upper casting, and a' the side boards of the lower casting.

B is the feed-hopper secured between the upper portions of the stationary boards a .

B' is the upper shaking-shoe, and C the lower shaking-shoe.

40 D is the fan-case, provided in opposite sides with eyes or openings d in the usual manner, and d' represents the horizontal fan-shaft turning in bearing d^2 , secured to the stationary frame A.

45 E are the fan-blades, each of which is con-

nected with a hub, E' , secured to the fan-shaft by two outwardly-diverging arms or branches, e . The two arms of each blade are arranged with their inner ends in tapering or 55 V-shaped sockets e' , formed in the hub E' , and are secured therein by screws or other suitable means. The inner ends of the arms e are preferably made round, and their contiguous portions are chamfered, so as to fit 60 squarely against each other. The hub E' is preferably divided longitudinally to facilitate casting the hub, and the parts thereof are secured together by bolts, as shown in Figs. 5 and 7. By this construction the arms 65 are secured to the fan-blades near the center of the blades, thereby leaving the eyes d of the fan-easing unobstructed, and allowing a free ingress of air and producing an even and uniform blast through the machine. The 70 diverging arms e form with the fan-blade a triangular frame, which construction renders the connection between the hub and blade rigid and prevents warping of the arms and blade.

75 f represents the screen of the upper shaking-shoe, which is supported at its inner end upon one of a vertical series of brackets, f' , formed on metallic plates f^2 , secured to the inner sides of the shaking-shoe at or near its 80 inner end, and whereby the inner end of the screen can be raised or lowered to give the same the proper inclination.

The screen f is provided at its opposite end with laterally-projecting pins g , which engage 85 in one of a series of undercut notches, g' , formed in plates g^2 , secured to the inner sides of the shoe at its outer end. By placing the supporting-pins of the screen in a higher or lower pair of notches its outer end can be 90 adjusted to the proper height. The shoulders of the undercut notches g' retain the pins g in the notches and prevent the same from being accidentally moved out of the notches. The plates f^2 serve as cleats, which 95 stiffen the sides of the shaking-shoe and prevent warping thereof.

H is a feed-board arranged at the upper end of the upper shaking-shoe, B', below the feed-hopper B. The feed-board H is provided with 100 a removable extension, H', the inner end of which abuts against the outer end of the

board H and is flush with the latter. The extension H' is provided at its outer end with laterally-projecting pins or studs h, which are arranged in inclined notches h', formed in the upper edges of the shaking-shoe. The inner end of the removable extension is supported by a bar, h², secured to the upper side of the extension and extending beyond the inner end thereof, and overlapping the adjacent portion of the feed-board, as clearly shown in Fig. 6.

h³ is a deflector secured to the top of the feed-board H, whereby the grain is deflected toward the center of the screen f and prevented from falling upon the side frames of the latter and escaping the screening action. The bar h² fits against the end of the deflector h³ when the extension H' is employed, and forms a continuation of said deflector.

20 In operating upon light material it is desirable to discharge the same at or near the center of the screen f, in which case the removable extension H' is employed, while in operating upon heavy material, which requires 25 a more thorough screening, it is desirable to discharge the material upon the inner end of the screen. In this case the extension H' is removed from the shoe by simply lifting its pins h out of the inclined notches h'. By inclining the latter, as shown, the inner end of the extension H' is firmly held against the adjacent end of the feed-board H when the extension is arranged in the shoe.

30 The upper shaking-shoe vibrates longitudinally, and is supported near its inner end by ordinary hangers, i, and near its outer end by vertically-adjustable hangers J. Each hanger J is pivoted at its lower end to the shoe B', and is provided at its upper end with a stud 35 or pin, j, which is adapted to engage in one of a series of semicircular notches or bearings, k k' k², formed in a curved plate, K, secured to the side of the casing a. The upper ends of the hangers J pass through curved slots k³, 40 formed in the plates K, and bear against the outer sides of said plates.

45 The notches k k' k² are arranged at different elevations on the plate K, the notch k being higher than the notch k', and the latter 50 higher than the notch k², so that by placing the pins j of the hangers J into a higher or lower notch the outer end of the shoe will be given a vertical throw of greater or less extent. In this manner the inner end of the 55 screen f receives a rising-and-falling motion, which, in conjunction with its longitudinal vibration, tosses the grain forwardly and upwardly into the blast produced by the fan, thereby enabling the latter to effect a more 60 thorough separation of the light from the heavy material and effectually preventing the meshes of the screen from becoming clogged. The notches k k' k² are so arranged that they will be concentric with the lower 65 pivots of the hangers J when the latter are at the outer extreme of their movement, as shown in Fig. 2.

In treating dry material the studs of the adjustable hangers J are arranged in the middle notch, k', while when damp material is treated, which is liable to clog the meshes of the screen, the hangers are arranged in either of the notches k k², as may be necessary to give the screen the requisite throw to sufficiently agitate the material and to prevent 75 clogging.

70 L represents plates hinged to the outer sides of the plates K, and provided at their lower edge with semicircular notches or bearings l, which coincide with the notches of the 80 plates K when the plates L rest against the same. The notches l bear against the upper side of the pins j of the hangers, and prevent the pins from being accidentally moved out of their bearings.

85 m m' represent the screens of the lower shoe, C. The lower screen, m', is provided at its outer end with laterally-projecting pins, which engage in one of a series of notches, m², formed in the end of the side frames of 90 the screen, so that the lower end of the screen can be raised and lowered to change its inclination, as may be desired. The upper cross-bar, m³, of the screen m' engages behind a cross-piece, m⁴, secured to the shoe C, 95 and thereby holds the screen against longitudinal movement in the shoe. The upper screen, m, is provided at its outer end with laterally-projecting pins n, which engage in one of a series of undercut notches, n', 100 formed in metallic plates n², secured to the inner side of the shoe at the outer end thereof, whereby the outer end of the screen can be adjusted vertically to give the same the proper angle. The tail end of the upper screen, m, 105 abuts against the upper end of the lower screen, m'. The lower shoe, C, also vibrates lengthwise of the machine, and is supported at its upper end by ordinary hangers, O, pivoted to the side of the case a', and at its opposite end by adjustable hangers O', similar 110 to the hangers J of the upper shaking-screen, so as to have a compound longitudinal and vertical movement like the latter.

115 p represents a vertical rock-shaft supported at its ends in bearings p', attached to the main frame A of the machine. This rock-shaft is set in motion by a connecting-rod, p², which is attached at one end to a crank-disk, p³, on the fan-shaft d', and at its opposite end 120 to an arm, q, secured to the outer side of the rock-shaft p.

125 q' is an arm secured to the rock-shaft p at right angles to the arm q, and q² is a connecting-rod extending from the arm q inwardly through an opening in the lower side board, a, and which connects at its inner end with a toggle, r s, arranged longitudinally underneath the upper shoe, B', and attached with one of its links to the shoe and with the other 130 to a bearing, r', secured to a cross-piece, r², of the casing. The rocking movement of the shaft p produces a reciprocating movement in the rod q² and a lateral movement in the tog-

gle r s, which latter swings outwardly on both sides of the longitudinal center line of the shoe, as indicated by dotted lines in Fig. 5, producing two strokes of the shaking-shoe for every revolution of the crank-disk p^3 , and imparting a short and rapid vibratory movement to the shoe.

The lower shoe, G, is actuated from an arm, t , secured to the rock-shaft p by means of a connecting-rod, t' , and toggle t^2 t^3 in a manner similar to the upper shoe, B'. The link t^2 of the toggle is pivoted to a cross-piece arranged in the lower portion of the machine, and the link t^3 is pivoted to an arm, t^4 , secured to the under side of the screen.

I claim as my invention—

1. The combination, with the fan-shaft d' and fan-blades E, of the hub E', mounted on said shaft and provided with sockets e' , and the outwardly-diverging arms e , secured with their inner ends in said sockets and with their outer ends to the fan-blades, substantially as set forth.

2. The combination, with the upper shaking-shoe, provided in its sides with notches h' , of the feed-board H, secured to said shaking-shoe, and a removable extension, H', having pins h engaging in the notches h' , and provided with a supporting-bar, h^2 , overlapping the end of the feed-board H, substantially as set forth.

3. The combination, with the shaking-shoe B', provided in its sides with inclined notches h' , and the feed-board H, provided with a deflector, h^3 , of the removable extension H', having pins h engaging in the notches h' , and provided with a supporting-bar, h^2 , overlapping the outer end of the feed-board and forming a continuation of the deflector h^3 , substantially as set forth.

4. The combination, with the lower shoe, C, provided at its upper end with a plate having a series of undercut notches, n' , and at its lower end with a series of notches, m^2 , of the lower screen, m' , provided at its lower end with supporting-pins engaging in the notches m^2 , and having an upper cross-bar engaging with a cross-piece, m^4 , secured to the frame of the shoe, and an upper screen, m , abutting with its lower end against the lower screen, m' , and provided at its upper end with supporting-pins engaging in the undercut notches n' , substantially as set forth.

5. The combination, with the stationary frame and shaking-shoe, of adjustable hangers J, pivoted at one end to the shoe and provided at their opposite ends with pins j , plates K, having an opening or slot in which the upper portions of the hangers are arranged, and with a series of notches, k k' k^2 , for receiving said pins, and plates L, hinged to the plates K and bearing with their lower edges upon said pins, substantially as set forth.

6. The combination, with the stationary frame and a longitudinally-vibrating shoe, of longitudinal toggle-links connecting the shoe with the stationary frame, a transverse driving-shaft having a crank-disk, an upright rock-shaft having two actuating-arms arranged about at right angles to each other, a rod connecting one of said arms with said crank-disk, and a rod connecting the other arm of the upright shaft with said toggle-links at or near the joint thereof, substantially as set forth.

Witness my hand this 26th day of March, 75
1888.
